UNITED STATES PATENT OFFICE

JEAN DIEUX, OF PARIS, FRANCE

PHONOGRAPH PICK-UP APPARATUS

Application filed October 20, 1928, Serial No. 313,708, and in France December 8, 1927.

My invention relates to electro-magnetic pick-up apparatus for the conversion of the mechanical vibrations of a stylus resting in the grooves of a phonograph or like record into corresponding electric oscillations.

The object of the invention is to amplify the vibrations of the moving armature so as to increase the variations of the magnetic field and the corresponding sonorous vibrations.

A further object comprises the rapid damping, in as simple a manner as possible, of the vibrations of the moving armature so as to avoid the superposition of these vibrations on the armature, which would be detrimental to its working.

These objects are attained by providing the apparatus with the characteristic features of the following specification, and particularly those set forth in the accompanying claims.

The preferred form of the invention is shown somewhat diagrammatically in the accompanying drawings, wherein Figs 1 and 2 are, respectively, a vertical elevation and a plan of an electromagnetic pick-up with the near part of the casing removed in each case.

The electromagnetic phonograph pick-up comprises a moving armature 1 the horizontal arm 1' of which extends through the coil 2 of an electromagnet having a fixed core 3. The winding 2 is connected by the leads 4 to the terminals 5, 6 connected in turn with an amplifier (not shown). This horizontal arm 1' has, within the coil 2, an expanded part 15, (Fig. 2,) which is also thickened, as shown at 16, Fig. 1, so as to re-inforce the action of the magnetic field of the electromagnet 2, 3. The moving armature 1 is bent at 7 to provide a vertical arm 1² which carries the stylus 8 which rests on the phonograph record 9.

The vertical arm 1² extends through and is engaged in a plug 10 formed of a pliant, elastic or flexible substance, such as rubber. This plug forms a damper, and it also closes the casing 11 which contains and supports the aforesaid parts.

The moving armature is also provided

with a vertical extension 1³ which combined with the vertical arm 1² gives the said armature the form of the letter T lying on its side in a vertical plane. This vertical extension 1³ is engaged in a ring 1⁴ also formed of a pliant, elastic or flexible material. The ring is connected with the casing 11 by a support 17 and co-operates with the plug 10 to damp the oscillations of the moving armature 1.

The aforesaid electric pick-up has numerous advantages. Firstly, the vibrations of the stylus 8, under the action of the grooves in the record 9, are amplified by the horizontal lever arm 1¹ of the armature, and this produces considerable variations in the flux of the electromagnet and perceptible variations in the current passing through its windings.

Moreover, the vibrations of the stylus are very rapidly damped by the combined action of the two dampers 10 and 14, which are placed on either side of the horizontal arm 1¹ of the moving armature.

These dampers serve also as a support for the moving armature, so that known supporting devices including pivots, forks, etc., which are usually complicated and fragile devices, can be dispensed with.

What I claim as my invention and desire to secure by Letters Patent is:—

1. In an electromagnetic phonograph pick-up apparatus, an electromagnet, a moving armature bent so as to form two arms, one of said arms moving in the magnetic field of said electromagnet, and having an expanded portion near the coil of said electromagnet, a stylus mounted on the other arm of said moving armature so as to engage with the surface of the phonograph record, the vibrations of said stylus being amplified by the first named arm of said moving armature.

2. In an electromagnetic phonograph pick-up apparatus, an electromagnet, a moving armature bent so as to form two arms, one arm moving in the magnetic field of said electromagnet and being thickened near the coil of said electromagnet, a stylus mounted on the other arm of said moving armature so as to engage with the surface of the phonograph record the vibrations of said stylus being am-

plified by the first named arm of said moving armature.

3. In an electromagnetic phonograph pick-up apparatus, an electromagnet, a moving armature bent so as to form two arms, one of said arms moving in the magnetic field of said electromagnet, the other arm being substantially perpendicular to the first named arm and having an extension so as to form a **T** with the first named arm, and guiding means being provided on said other arm and the extension of this other arm, a stylus mounted on the other arm of the moving armature and adapted to engage with the surface of the phonograph record, the vibrations of the stylus being amplified by the first said arm of said moving armature.

4. In an electromagnetic phonograph pick-up apparatus, an electromagnet, a moving armature bent so as to form two arms, one of said arms moving in the magnetic field of said electromagnet, a stylus mounted on the second arm of said moving armature and engaging with the grooves of the phonograph record, the vibrations of the stylus being amplified by the first mentioned arm of said moving armature, and two supports of flexible material suspending said moving armature at two different places and damping the vibrations thereof.

5. In an electromagnetic phonograph pick-up apparatus, an electromagnet, a moving armature bent so as to form two arms, one of said arms moving in the magnetic field of said electromagnet and the other arm being substantially perpendicular to the first said arm, and having an extension so as to form a **T** with the first said arm, a stylus mounted on said other arm and adapted to engage with the surface of the phonograph record, the vibrations of said stylus being amplified by the first said arm of said moving armature, and two supports of pliant material mounted, one on said other arm of the moving armature and the other on the said extension of said arm, said two supports carrying the suspended moving armature at two different places and damping the vibrations thereof.

6. In an electromagnetic phonograph pick-up apparatus, an electromagnet, an armature adapted to vibrate in the magnetic field of said electromagnet, a stylus mounted on said moving armature so as to engage with the grooves of the phonograph record, a casing containing said parts, a plug of pliant material closing said casing and engaged on the moving armature to damp the vibrations thereof.

7. In an electromagnetic phonograph pick-up apparatus, an electromagnet, a moving armature in the magnetic field of said electromagnet, a stylus mounted on said armature so as to engage with the surface of the phonograph record, a casing containing parts, a plug of resilient material closing said casing

and engaging said armature to damp the vibrations thereof, and a ring of resilient material engaging said armature and cooperating with said plug to damp the vibrations of said armature.

8. In an electromagnetic phonograph pick-up apparatus, an electromagnet, a moving armature bent so as to provide two arms, one of said arms moving in the magnetic field of said electromagnet, the other arm being substantially perpendicular to the first said arm, and having an extension forming a **T** with the first said arm, a stylus mounted on the other arm of said armature and engaging with the surface of the phonograph record, the vibrations of said stylus being amplified by the first said arm of said armature, a casing containing the said parts, a plug of flexible material closing said casing and engaging said other arm of said armature, and a ring of flexible material carried by said casing and engaging the extension of said other arm of said armature, said ring cooperating with said plug to damp the vibrations of said armature.

In testimony whereof I have signed this specification.

JEAN DIEUX.
